CLAIM

The ornamental design for an combined electric toothbrush and toothbrush holder, substantially as shown and described.

DESCRIPTION

FIG. 1 is an upper right frontal perspective view showing an combined electric toothbrush and toothbrush holder according to my new design;

FIG. 2 is a rear perspective view from a bottom angle thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an upper frontal exploded view in perspective thereof showing the electric toothbrush removed from the holder; and,

FIG. 10 is an upper rear view in perspective thereof showing the electric toothbrush removed from the holder.

The broken lines in the drawing depict portions of the combined electric toothbrush and toothbrush holder that form no part of the claimed design.
